UNITED STATES PATENT OFFICE.

WILLIAM K. ACHERT, OF CINCINNATI, OHIO.

ADVERTISING-CARD.

SPECIFICATION forming part of Letters Patent No. 793,261, dated June 27, 1905.

Application filed November 14, 1904. Serial No. 232,667.

To all whom it may concern:

Be it known that I, WILLIAM K. ACHERT, a citizen of the United States, and a resident of Cincinnati, in the county of Hamilton and State of Ohio, have invented a certain new and useful Improvement in Advertising-Cards, of which the following is a full, clear, and exact description, reference being had to the accompanying drawings, which form a part of my specification.

My invention relates to an advertising novelty in the nature of a card formed by folding a sheet or blank of cardboard upon itself and the two sides or walls secured together in such a manner as to permit of their being slightly distended upon slightly depressing one end of the card, so as to create a current of air which will pass through an aperture in one of the side walls in the nature of a whistle, the card being intended to receive any advertising matter it is desired to have placed thereon, as will more clearly appear and be understood from the following specification.

In the drawings, Figure 1 is a blank or sheet of paper or cardboard cut and scored to form my improved advertising-card. Fig. 2 is a perspective view of the card formed from the blank shown in Fig. 1, with its top end slightly depressed, whereby the side walls are somewhat distended. Fig. 3 is a sectional view of my improved card, taken on the line *xx* of Fig. 2.

Like letters of reference indicate identical parts in the respective figures.

The card is preferably constructed from a sheet of heavy paper, which is scored at *a* to form the two sides A B and permit of its being folded upon itself. The sides are provided with extensions *b*, *c*, *d*, and *e*, which are scored to fold inwardly. The extensions *c* and *d* are intended to be glued together with any suitable adhesive material on the inside of the card, and the extensions *b* and *e* are likewise intended to be glued together, as will be seen in Fig. 1. The side B is preferably cut at its one end in the curved or scooped-out manner indicated at Fig. 1, while the side A is made somewhat longer than B.

The side A is provided with the score-marks *g*, *h*, and *i*, the score-mark *g* being such as to

permit the extension of the side A to lap inwardly to permit the portion of the blank intermediate the score *i* and the edge of the blank to be glued to the opposite side B of the card. These score-marks *h* and *i* permit the end of the card at which they appear to be pressed downwardly to force the sides A and B apart, these scores producing at the end of the card what might be termed a "bellows fold."

One of the sides of the card—for example, B—is provided with a small aperture *k*, and secured to that side about the hole or aperture *k*, on the side of the blank which comes inside the card, is a ring *l* of heavy cardboard or other suitable material, which may be glued or otherwise secured to the side B. This ring *l* has secured to it a thin disk of paper *m*, which is provided with an opening *n*, corresponding with the aperture *k*. It will be seen that a chamber *p* is formed intermediate of the side B and the disk of paper *m*.

The different extensions *b*, *c*, *d*, *e*, and *f* on the sides of the blank or card are of course tightly secured or glued to each other or to the opposite wall, so as to make the card airtight, except for the aperture or opening *k*.

It will be seen that by taking the card and lightly pressing down on the end having the bellows fold that the air is drawn into the card, and by releasing the bellows fold the sides are permitted to come together, which forces the air out of the card. The air rushing in and out, by reason of the manipulating or depressing just spoken of, produces a whistling sound through the aperture *k*, by reason of the chamber *p*, formed by the ring *l* with its disk *m*, having the aperture *n*.

I have described what I believe to be the preferable form; but it will be readily understood that the card may be provided with a bellows fold at both ends, and instead of providing the blank with the extensions *d* and *e* these may be omitted, simply having the blank with the extensions *b* and *c*, or vice versa, and I do not wish to be understood as limiting myself to the exact construction shown and described; but

What I wish to claim as my invention, and secure by Letters Patent, is—

1. An advertising-card having two walls, extensions intermediate of and secured to said walls, the one extension scored to form a bellows fold, said bellows fold normally distending the walls, an aperture in one of said walls, a ring secured on said wall about the aperture, and a disk secured to the other side of said ring and provided with an aperture corresponding with the aperture in said wall, substantially as shown and for the purpose described.
2. An advertising-card having two walls comprising side portions integral with each other, side and end extensions glued together,

one of the end extensions being scored to 15 form a bellows fold and normally distend the walls, said bellows-fold extension being provided with a flap secured to the other side or wall, an aperture in one of said sides, a ring secured on said side about the aperture, and a 20 disk secured to the other side of said ring and provided with an aperture corresponding with the aperture in said side, substantially as shown and described.

WILLIAM K. ACHERT.
